UNITED STATES PATENT OFFICE.

JOHN TURNER AND ANTHONY BUXTON, OF MANCHESTER, ENGLAND, ASSIGNEES TO
THE RUBBER PATENTS LIMITED, OF COWLEY, ENGLAND, A JOINT STOCK COMPANY.

FOOT-BALL, PUNCH-BALL, AND SIMILAR PLAYING-BALL.

964,888.

Specification of Letters Patent. Patented July 19, 1910.

Application filed April 28, 1909. Serial No. 492,701.

To all whom it may concern:

Be it known that we, JOHN TURNER and ANTHONY BUXTON, both subjects of the King of Great Britain and Ireland, and residents of Manchester, in the county of Lancaster, in the Kingdom of Great Britain, have invented certain new and useful Improvements in Foot-Balls, Punch-Balls, and Similar Playing-Balls, of which the following is a specification.

This invention relates to the casings of footballs, punch balls and like playing balls made of segments of canvas coated with india-rubber and sewn or cemented together, and consists in improvements thereon. It has been found in practice that the aforesaid balls are somewhat stinging to the head, hands or feet in consequence of the canvas being stretched to its full extent when the bladder inserted into the casing is fully inflated, and their resiliency is somewhat too great for certain purposes.

The object of this invention is to remedy this inconvenience and to make the balls feel softer and thicker like leather balls, while retaining their waterproof quality.

On the drawing appended hereunto the improved casing is shown in Figure 1 in outside view, and in Fig. 2 in horizontal section, without the bladder.

The object of our invention is attained by combining with the outer casing made of water proofed canvas or canvas and india-rubber, an inner shell or liner of soft felt, or equivalent thick and soft material, such as flannel, flannelette or the like.

On the drawing *a* represents a shell made of segments of rubber proofed canvas sewn together and of such size and shape, that when they are stretched by the inflation of the bladder *e* the ball assumes the required shape. To this an outer shell *b* is cemented which may be of rubber coated canvas or rubber. The inner shell or liner *c* formed of soft felt or its equivalent is formed of segments of such size, that when the ball is inflated, these segments are not stretched or only very slightly so, so that the softness of the material is not impaired. The segments forming the liner may be sewn to the seams of the outer casing after it has been vulcanized, as shown in the drawing, or they may be sewn together so as to form a complete

shell open at the lacing hole, and attached to the outer casing by being sewn thereto at 55 the lacing hole *d*. By these means a ball casing having a soft and thick feel is obtained, and the resiliency of the ball is somewhat moderated, so that it feels and acts like a leather ball, while its waterproof quality is retained.

We claim as our invention:

1. An athletic ball or bag casing provided with an opening for receiving a bladder and comprising in combination, an intermediate 65 cover member, an outer cover member secured to said intermediate cover member, a lining of soft fabric secured to and within said intermediate cover, and a bladder within said lining, said lining being of sufficiently increased size with respect to the size 70 of the intermediate cover so as to lie in a flat, unfolded and loose condition against the intermediate cover upon inflation of the bladder. 75

2. An athletic ball or bag provided with an opening and comprising in combination, an intermediate cover member composed of a plurality of sections, an outer cover member composed of a plurality of sections cemented to the intermediate member, a lining composed of a plurality of sections sewed to the intermediate sections, and a bladder within said lining, said lining sections being formed of soft material and being of sufficiently increased size with respect to the intermediate sections as to remain loose and lie flat against said intermediate sections upon inflation of the bladder. 80 85

3. An athletic ball or bag casing provided with an opening and comprising in combination, an outer cover member, an inner lining, and a bladder within the lining, said lining being of sufficiently increased size with respect to the outer cover member as to 95 lie loosely and flatly against the same when the bag is inflated, substantially as and for the purposes set forth. 90

In testimony whereof we have hereunto set our hands in the presence of two witnesses. 100

JOHN TURNER.
ANTHONY BUXTON.
